CLAIM

I claim the ornamental design for animal approachability display tag set, as shown.

DESCRIPTION

The file of this patent contains at least one drawing/photograph executed in color. Copies of this patent with color drawing(s)/photograph(s) will be provided by the Office upon request and payment of the necessary fee.

FIG. 1 is a perspective view of an animal approachability display tag set according to my present design, shown attached to animal collars in an environmental view;

FIG. 2 is a perspective view thereof, but shown separately for clarity of illustration;

FIG. 3 is a front view thereof;

FIG. 4 is a rear view thereof;

FIG. 5 is a first side view thereof;

FIG. 6 is a second side view thereof;

FIG. 7 is a top plan view thereof; and,

FIG. 8 is a bottom plan view thereof.

The broken lines illustrate environmental structure that form no part of the claimed design.
